UNITED STATES PATENT OFFICE.

JOSEPH LA PORTE, OF LOMITA, CALIFORNIA.

PARACHUTE CONTAINER AND EJECTOR FOR AEROPLANES.

Application filed October 20, 1926. Serial No. 142,914.

My invention is a parachute container and ejector for aeroplanes.

An object of my invention is the construction of an aeroplane with a container for a parachute and means to eject the parachute by an air blast, such blast being caused by trapping some of the air through which the aeroplane is traveling and forcing same into the center of the parachute, thus ejecting the 10 parachute and at the same time partly expanding same.

Another object of my invention is in the manner of connecting the parachute to the aeroplane in order to sustain same if disabled or out of control and in the manner of 15 housing the cables or the like connecting the parachute in the container and the attaching devices to the aeroplane.

Another feature of my invention is in the 20 controlling of a trap type of chute for forcing the air into the parachute.

My invention also comprises equipping the aeroplane with guards which prevents the 25 parachute from becoming entangled in the rudders or fins.

My invention is illustrated in the accompanying drawings, in which:

Figure 1 is a side elevation partly broken away of an aeroplane equipped to contain 30 and eject parachutes in accordance with my invention;

Fig. 2 is a bottom view taken in the direction of the arrow 2 of Fig. 1;

Fig. 3 is a side elevation partly broken 35 away, showing the aeroplane being sustained by the parachute;

Fig. 4 is a section on the line 4—4 of Fig. 3 in the direction of the arrows, this being through the chute and the ejector.

The aeroplane is designated generally by 40 the numeral 1 and has an air passage 2 extending from the bottom in an inclined manner upwardly towards the rear. This passage is preferably formed with a rear 45 wall 3, a front wall 4 and side walls 5. These at their lower edges are spaced apart substantially to the largest dimensions the aeroplane will allow and are contracted into a discharge passage 6, this being shown as a 50 circular.

The container for the parachute is designated generally by the numeral 7 and has a 55 floor 8 and side walls 9, these walls being preferably circular and terminating at the top 10 of the fuselage. The parachute 11 is folded inside the container, the projecting

end 12 of the discharge passage extending above the floor, the top of the parachute being drawn over the discharge end and the sides being folded between such end and the side walls of the container. The ropes and cables 13 of the parachute are preferably connected to a ring 14, such ropes being packed in the container, the ring resting on the floor 8. Cables 15 extend from the ring to eyes or the like 16 on the aeroplane structure so as to sustain the aeroplane from the parachute when the parachute is opened. There are preferably channels 17 formed in the aeroplane leading from the 70 container to these eyes. Should the cables 15 require to be of considerable length these may be coiled in a receptacle 18 between the eyes 16.

It is desirable to enclose the containers and 75 the channels having the cables and also the cables in the receptacle 18 should they be coiled there, by a suitable cover 19. This would be made of readily tearable material so that when the parachute is blown out this 80 cover will be ripped or otherwise opened allowing the parachute to expand freely and the ropes and cables to be drawn out.

An air chute is designated generally by 85 the numeral 20 and is constructed by having a hinged trap door 21 mounted on a transverse pintle 22 extending across the aeroplane at the bottom at the junction of the bottom of the aeroplane with the rear wall 3 of the lower air passage 2. Arms 23 are 90 rigidly connected to the trap door and by means of springs 24 connecting such arms to a fixed part of the aeroplane there is a constant tendency to spring or open the trap door. This door is held closed by a latch 25. 95 such latch being shown as having the spring 26 holding same in engagement with the door.

There is a foot pedal 27 to be operated by 100 the aviator and a cable 28 connecting from the foot pedal to the latch to trip same. Rigidly connected to the trap door are side walls 27 which when the door is closed extend upwardly on opposite sides of the side walls 5 of the air passage. There is preferably 105 a flange 30 or the like to prevent the trap door from opening too far when released.

In order to prevent the parachute from 110 becoming entangled in the rudders a cage 31 is constructed at the rear part of the fuselage. This preferably has a series of arches

32 extending transversely across the tail end of the aeroplane and a series of longitudinal bars 33 secured to the arches and drawing together towards the fuselage at a considerable distance forward of the control rudders. As the spaces between the bars become wider towards the stern of the aeroplane, the parachute will not become wedged in the cage and should it sweep along the upper part of 10 the fuselage the parachute will clear the control rudders.

The manner of operating of the ejector is substantially as follows:

When the aviator decides it is necessary 15 to release the parachute, he merely has to step on the pedal 27 which releases the latch 25 so that the springs 24 cause the springing or downward opening of the trap door 21, this carrying the rigid side walls 29 and 20 forming a chute 20 extending below the bottom of the aeroplane. This chute has the two side walls and the bottom formed by a trap door.

The air is then forced upwardly through 25 the lower passage 2 and the upper passage 6, thereby causing the inflation of the parachute and blowing same out of the container. As above mentioned the parachute causes the ripping or opening of any covering employed to close in the container. The parachute receives a direct blast of air through the chute and the air passages until it is entirely clear of the aeroplane and then catches the air and expands to its normal diameter. 30 The ropes 13 are pulled out of the container and join the cables 15. It is intended that the aeroplane will be carried on an even keel when the parachute is expanded to the fullest extent as shown in Fig. 3.

40 Although the aeroplane may be falling nose down when the trap door is opened and the parachute projected, when the parachute properly catches the air it will draw the aeroplane into a horizontal position, the 45 wings of the aeroplane then functioning to retard the fall of the aeroplane and parachute.

The arrangement of the chute and air passages are sufficient to actuate the parachute 50 no matter how the aeroplane falls. Should it stall and fall tail first for a short distance, it will usually reverse its position, coming nose down. Hence the strong draft of air would be forced into the chute, ejecting the 55 parachute.

Although I have illustrated the parachute as being connected to the aeroplane, it is to be understood that similar device or devices could be utilized to discharge individual 60 parachutes for the pilot, the crew of the aeroplane and any passengers carried.

Various changes may be made in the principles of my invention without departing from the spirit thereof as set forth in the 65 description, drawings and claims.

What I claim is:

1. In the art described, the combination of an aeroplane having a container, a parachute housed therein, an air passage through the aeroplane to the container to eject the parachute, means to open and close said passage, and a cage at the rear end of the aeroplane to guide the parachute clear of control rudders or the like. 70

2. The combination of an aeroplane having 75 a container with an inclined floor, side walls extending upwardly and rearwardly from the floor, an air passage extending through the floor and downwardly in a forward direction, the projecting end of the 80 passage being above the floor, a parachute folded in the container with the center part across the passage and the sides folded between the passage and the side walls of the container, a trap door having side walls 85 forming an air chute, a latch to normally hold same closed, ropes and cables connected to the parachute, means connecting the cables to the aeroplane, and means controlled by a pilot to release the trap door. 90

3. In the art described, the combination of an aeroplane having a container with a rearwardly inclined floor, an air passage extending from the bottom of the aeroplane at 95 an angle upwardly and rearwardly through said floor, a trap door pivoted at its rearward edge adjacent the rear side of the passage and having side walls attached to same forming an air chute, a latch to hold the trap door closed, means to open the door on 100 release of the latch, the discharge passage extending above the floor of the container whereby the parachute may be packed in the container with the central part over the air passage and the sides folded between the 105 passage and the sides of the container.

4. In the art described, the combination of an aeroplane having a fuselage with a container mounted therein, the floor of such container being inclined rearwardly and 110 downwardly relative to the horizontal and having an opening through the top of the fuselage, an air passage extending downwardly and forwardly from the floor of the said compartment and having an opening 115 through the bottom of the fuselage, a trap door forming a closure for the bottom of the said passage with a latch to hold and release the door, and a parachute folded in the container with part of the parachute 120 extending across the upper end of the said air passage.

5. In the art described, the combination of an aeroplane having a fuselage, a container built in said fuselage and having a 125 downwardly and rearwardly inclined floor having reference to the horizontal, a structure forming an air passage extending downwardly and forwardly from the said container and having a discharge end extending 130

- above the floor of the said container, leaving a space between the discharge end and the outside of the container, a trap door forming a closure for the lower part of the 5 passage at the bottom of the fuselage, and means to hold said trap door open on a downward and forward inclination, a readily removable cover over the top of the container, a parachute housed in the container 10 and having part of same folded in the space around the discharge end of the said air passage and part of the parachute extending across the open upper end of the said air passage.
- 15 6. In the art described, the combination of an aeroplane having a fuselage with controls on the rear end thereof, a container mounted in the fuselage having a down-
- wardly and rearwardly inclined floor having reference to the horizontal with said container having an open top through the top of the fuselage, a structure having a downwardly and forwardly inclined air passage leading from the floor of the container to the bottom of the fuselage, a trap door 20 forming a closure for said air passage, a parachute folded in the container and having a part extending over the open end of the said air passage, a readily removable cover over the said container, and guards 25 secured to the fuselage to prevent contact of the parachute with the said controls.
- In testimony whereof I have signed my name to this specification.

JOSEPH LA PORTE.
